CLOTHESPIN CONTAINER

Cecil C. Meyers, Ottawa, Ontario, Canada

Application May 13, 1955, Serial No. 508,258

5 Claims. (Cl. 150—1.8)

The invention relates to an improved clothespin container for use on a clothesline or for suspension from one's clothing.

The present invention fills a need for a clothespin container which is convenient in use either suspended from a clothesline or from one's clothing, while providing a weather-proof and dirt-proof container for the clothespins.

A clothespin container according to the invention comprises a pouch of flexible material having an opening along one edge. Each edge of the opening is fitted with an exteriorly generally rectangular-shaped bail, the one bail forming a hook for hanging the pouch from a clothesline while the other bail is adapted to be drawn through the bail which forms a hook to close the opening in the pouch. In this way the material of the pouch is overlapped at the opening to provide a weather-proof and dirt-proof closure. Preferably each of the corners of the material of the pouch at the opening is turned inward against the corresponding side of the pouch and is sewn into the adjacent hem. In this way the ends of the opening into the pouch are drawn inward to provide additional protection against the intrusion of water or dirt into the pouch. Also, it is preferred that the bail which is adapted to be drawn through the other bail is shaped so that after closing the opening into the pouch it is adapted to pass over at least one corner of the pouch at the side opposite to the opening thereby locking the pouch closed.

A clothespin container according to the invention can be conveniently hung on a clothesline by the bail which is hook shaped and for use with a pulley type clothesline a hook can be provided to anchor the container near one pulley. The container is opened by sliding one bail through the other, and the bails serve to hold the container open and to provide a rectangular-shaped opening which is convenient for removing and returning clothespins to the pouch.

If desired, the container can be made water-proof by drawing the one bail through the other as described above, and the bag left hanging on the clothesline when not in use. The container is also adapted to be used by suspending it from the bib of an apron. In this case the bib of the apron can be passed through the hook-shaped bail and the container will hang open in a convenient position.

The invention will be further described with reference to the accompanying drawings in which:

Figure 1 is a perspective view of a clothespin container according to the invention suspended from a pulley type clothesline with the pouch open;

Figure 2 is a perspective view of the clothespin container shown in Figure 1 removed from the clothesline and with the pouch closed; and

Figure 3 is a detailed view of one end of the clothespin container with one side of the container removed.

As shown in the drawings the clothespin container comprises a pouch 10 of a flexible material which may be a water-proof or semi-water-proof type of cloth. The pouch 10 has an opening 11 extending along one edge and part

2

way down each end 12 and 13 of the pouch 10. Each side of the opening 11 has an open-ended hem 14 and 15 sewn into it as shown in Figures 1 and 2. Each of the corners 16 of the material at the opening 11 is turned inward against the corresponding side of the pouch 10 and is sewn into the adjacent hem 14 or 15. This results in the ends 12 and 13 of the pouch 10 being drawn inward at the opening 11 as shown in detail in Figure 3.

Figure 3 shows one end 12 of the pouch 10 with the near side of the pouch 10 removed. As indicated by the broken line 30 the edges of material forming the sides of the pouch 10 are sewn together from the bottom of the pouch 10 up to a point 31 leaving corners 16. Each of the corners 16 is drawn inward of the pouch against the corresponding side of the pouch 10 and the edge 32 of each corner 16 is sewn into the adjacent hem 15 (or 14 in the case of the other side of the pouch). In this way the ends 12 and 13 of the pouch 10 are drawn inward of the pouch to make the closure (described below) along the opening 11 of the pouch more effective.

As shown in Figures 1 and 2 a generally rectangular-shaped bail 17 of wire is fitted into the open ends of the hem 14 by means of the U-shaped ends 18 of the bail 17. A generally rectangular-shaped bail 19 of wire is fitted into the ends of the hem 15 by means of its U-shaped ends which are similar to the U-shaped ends 18 of the bail 17. The free end 23 of each of the bails 17 and 19 is turned outward slightly and is completely within the hem. Each U-shaped end 18 of the bails is sprung inward of itself to permit insertion into the hem and upon release it urges the ends 23 against the inner surface of the hem. This keeps the pouch 10 firmly in position on the bails but, if desired, the pouch can easily be removed from the bails by pressing inward on the U-shaped ends 18. The bail 19 is doubled over on itself forming a hook for hanging the pouch 10 from a clothesline 20 as shown in Figure 1, and a hook 21 of wire is pivotally fastened to the bail 19 to anchor the clothespin container to a pulley 22 of the clothesline. As shown in Figure 1 the bail 17 is made large enough relative to the area of the opening 11 that, with the opening 11 at its maximum area, the bail 17 extends through and past the bail 19 thereby locking the bail 19 over the clothesline 20 to prevent accidental removal of the clothespin container from the clothesline, for example by wind.

The only materials required for the manufacture of the clothespin container are stiff wire and the cloth and thread which are required for the manufacture of the pouch. A bag suitable for holding up to 150 clothespins would require a piece of cloth 14 x 18 inches. Approximately 5 feet of wire is required for the manufacture of the bails and the hook. A grade of wire similar to that used in wire type coat hangers is suitable. The bails can be assembled or removed from the pouch at any time and this is an advantage in permitting shipment of the bails and the pouches separately.

In use the clothespin container may be suspended from a clothesline, as shown in Figure 1, or it may be suspended on one's person from the bib of an apron by passing the bib of the apron through the bail 19. In either case the rectangular-shaped bail 17 serves to provide a large easily accessible rectangular-shaped opening 11 into the pouch 10. Also the hook 21 may be extended in a vertical direction above the container to hook onto the clothesline thereby suspending the bag at a substantial distance beneath the clothesline. In this case, a clothespin may be used to prevent the hook 21 from sliding along the bail 19. When the bag is not in use it may be securely closed in the manner shown in Figure 2 by drawing the bail 17 through the bail 19 until the material on one side of the opening 11 overlaps that on the other side and one or both of the lower corners of the pouch 10

may be passed through the bail 17 as shown in Figure 2. In this way the bail 17 serves to lock the bag closed and to prevent entry of rain or dirt even when the container is hanging on a clothesline in a high wind.

What I claim as my invention is:

1. A clothespin container comprising a pouch of flexible material having an opening along one edge, said opening extending part way down each end of the pouch adjacent to said edge, an open-ended hem along each edge of said opening, an exterior generally rectangular shaped bail for each said hem, each bail extending out of one open end of the hem and into the other open end of the hem, one bail forming a hook for hanging said pouch from a clothesline, the other bail being adapted to be drawn through said one bail to close said opening.

2. A clothespin container as defined in claim 1 in which each corner of the material of the pouch at the opening is turned inward against the corresponding side of the pouch and is sewn into the adjacent hem.

3. A clothespin container as defined in claim 1 in which the bail adapted to be drawn through the other bail after

causing the opening into the pouch to be closed is adapted to pass over at least one corner of the pouch at the side opposite to said opening.

4. A clothespin container as defined in claim 1 in which each end of each bail extends only part way into the corresponding hem is turned back on itself in a U-shape having a free end, said free end being within the hem and turned outwards.

5. A clothespin container as defined in claim 4 in which the U-shaped end of each bail is sprung inward of itself to permit insertion into the corresponding hem.
